UNITED STATES PATENT OFFICE.

HULDA WALLMAN, OF NEW YORK, N. Y.

HEADDRESS.

Application filed June 29, 1926. Serial No. 119,503.

This invention relates to head dress, and has especial reference to the type of head dress disclosed in a Patent No. 1,539,706, granted to me.

5 The principal object of the present invention is the provision of an article of the indicated character which will embody novel means for adjusting the head encircling parts or bands thereof.

10 Another object is the provision of an ornamental head dress having means whereby distinctive adornments may be worn in combination with the head dress.

15 The nature of the invention and its distinguishing features and advantages will appear when the following specification is read in connection with the accompanying drawing, in which—

20 Figure 1 is a view of the head dress of the present invention in use.

Fig. 2 is a perspective view of the head dress itself.

Fig. 3 is a detail sectional view, on an enlarged scale, on the line 3—3 of Fig. 2.

25 Fig. 4 is a perspective view of one of the fastening elements.

The head dress, generally stated, comprises two parts 10 and 11 and means 12 for adjustably holding the parts 10 and 11 together to vary the head size thereof. Each of the parts 10 and 11 may be made of any suitable flexible material such as celluloid, and may consist of one or more head encircling bands. In the present instance each part 11

30 consists of a band 12 and a band 13 which bear a diverging relationship and terminate in a single end portion 14. The end portions 14 of each of the parts 10 and 11 has a multiplex keyhole slot 15, such slot providing

35 comparatively large circular portions 16 and restricted portions 17 joining the circular portion 16. Associated with each pair of the end portions 14 is a securing element 18 having a head 19 at one end, a comparatively

40 large head 20 at the opposite end, a cross sectional rectangular portion 21 between the heads 19 and 20, and a manipulating portion 22 on the head 20. The portion 21 of each element 18 is disposed in its related slots, 45 the head 19 being applied after the portion 21 is so disposed to prevent the element 18 from being removed. The portion 21 of each of the elements 18 may be disposed in either

of the registering circular portions 16 of the slots to thus hold the parts 10 and 11 in 55 the desired adjusted relationship to obtain the desired head size. This arrangement allows a relative pivotal movement of the parts 10 and 11. When it is desired to vary the head size, it is only necessary to turn each 60 of the elements 18, by manipulating the portions 22 respectively, one-quarter of a turn, which will permit the elements 18 to be slid from registering circular portions 16 occupied 65 to others.

In order to hold the hair with the desired effect, the band 12 of the part 10 on the inside thereof is provided with small combs 23 which engage locks of the hair at opposite sides of the head.

70 In order to permit of the use of an additional adornment such as feathers, flowers, or any others, the band 12 of the part 11 is provided with pairs of slits 24 which accommodate a portion of the particular adornment used.

75 From the foregoing it will be apparent that there has been described a head dress which is particularly suitable for use by women and girls having bobbed hair for confining folds of the hair with the desired effect, and in which provision is made for adjusting the head encircling parts or bands of the head dress.

I claim:

80 1. An ornamental head dress comprising two head encircling bands, means adjustably and pivotally connecting said bands together, said means consisting of headed elements each having a cross sectionally rectangular portion which coacts with portions of overlapping ends of said bands, said portions being provided by virtue of multiplex keyhole slots in each of the overlapping ends.

85 2. An ornamental head dress comprising two head encircling bands, means adjustably pivotally connecting said bands together, said means consisting of headed elements each having a cross sectionally rectangular portion which coacts with portions of overlapping ends of said bands, said portions being provided by virtue of multiplex keyhole slots in each of the overlapping ends, each 90 of said elements having a manipulating portion.

HULDA WALLMAN.
